Primary Examiner — Antoine D Davis*(74) Attorney, Agent, or Firm* — Seager Tufte & Wichkem LLC.(57) **CLAIM**

The ornamental design of the thermostat housing, as shown and described.

DESCRIPTION

FIG. 1 is a perspective view of a thermostat housing; FIG. 2 is a front elevation view of the thermostat housing of FIG. 1; FIG. 3 is a left elevation view of the thermostat housing of FIG. 1; FIG. 4 is a right elevation view of the thermostat housing of FIG. 1; FIG. 5 is a top view of the thermostat housing of FIG. 1; and, FIG. 6 is a bottom view of the thermostat housing of FIG. 1. The features shown in broken lines depict environmental subject matter only and form no part of the claimed design.
